UNITED STATES PATENT OFFICE

2,435,007

TUBULAR ELASTIC BRACE

Frederick D. Johnson, Rochester, N. Y., assignor
to Hickok Manufacturing Company, Inc.,
Rochester, N. Y., a corporation of New York

Application July 27, 1945, Serial No. 607,315

3 Claims. (Cl. 2-338)

1

This invention relates to elastic shoulder straps, and especially to braces, commonly known as suspenders.

Prior braces of the woven or fabric type, particularly those containing elastic material, tend to grip or frictionally engage the shoulder portions of the shirt when the wearer bends over, thus mousing the shirt and also causing non-uniform tension in the front and rear portions of the brace straps. This undesirable frictional engagement is accentuated if there is twisting of the straps through constant use, or if there is a narrowing of elastic straps. The twisting and narrowing further cause discomfort to the wearer, and shorten the life of the brace.

It is the primary object of the present invention to devise a brace or the like embodying elastic shoulder straps that are substantially frictionless relative to the shoulders or the shirt of the wearer, with the result that the tension is equalized in the strap ends that depend forwardly and rearwardly from the shoulder. In this connection, it is an object to provide a material for purposes of the present invention, in which elastic warp and fluffy woof are so made and related that the warp affords smooth parallel ribs longitudinally of the strip, with the woof substantially concealed.

It is another major object of my invention to provide an elastic brace or shoulder strap that can stretch longitudinally only, the width remaining constant under all conditions. The absence of narrowing under stretching also tends to prevent spiral twisting of the strap.

A further important object of this invention resides in the provision of a shoulder strap of tubular or hollow tape formation. Such formation affords smooth finished edges and resists the twisting that normally occurs in a plain flat strap; and, it also affords a somewhat ventilated strap in which the body-contacting wall can absorb perspiration that otherwise would pass into the visible outer wall of the strap.

It is a still further object to construct a tubular elastic shoulder strap from a flat strip of fabric by joining the edges at one side of the strap with a longitudinal seam, the seam threads being non-elastic but so arranged as to permit free and full longitudinal stretching of the strap.

The foregoing and other objects of the present invention will clearly appear from a study of the following description and the accompanying drawing:

In the drawing:

Fig. 1 is a perspective view of the front of a

2

complete pair of suspenders embodying a preferred form of my invention, one of the straps being turned back upon itself to show the seamed side surface;

Fig. 2 is an enlarged view of a section of the tubular strap material of Fig. 1, opened at one end and having a series of warp threads pulled away from the woof;

Fig. 3 represents a cross section taken on the plane of line 3-3 of Fig. 2, the clearances being exaggerated for clarity of illustration.

With continued reference to the drawing, a pair of substantially flattened tubular shoulder straps 4 have what may be called their "rear" ends secured, as by sewing, to a pair of conventional tabs 5. These tabs form channels for the reception of a conventional cord 6 of elastic or other suitable material the ends of which carry the usual eyelets 7 for connection to trouser buttons.

The other ends of the straps 4—which may be termed the "front" ends—pass in conventional manner through metal loops 8, and are turned backwardly upon themselves and fastened to the usual adjustment clamps 9. The loops 8 carry channeled tabs 10, each receiving a U-shaped member having slotted ends 13, all conventional.

Each tubular strap 4 is formed from a flat strip of material by folding one edge rearwardly; then folding the other edge portion twice to form a third smooth edge 14 (as best seen in Fig. 3); and sewing the associated edges together by stitches 15 that are rather loosely drawn, excessive tightness being avoided for a reason presently explained.

This seam may be completed by cementing the edges together in lieu of stitching; and this likewise is true of any other parts shown joined by sewing. Preferably in the case of the tubular strap, a pliable and resilient adhesive would be used at the seam.

The strip just mentioned is cut longitudinally from a sheet of woven fabric in which the warp threads, or at least the major part thereof, are elastic, but in which the woof is entirely inelastic.

As a result the strip, and hence the strap made therefrom, can be stretched longitudinally without any noticeable change in width. In order to obtain a minimum of friction between the strap and the shirt, the warp preferably comprises

prominent smooth elastic threads 16 which appear as ribs on the strap surface, alternated with finer inelastic spiraling threads 17 which appear as valleys between the ribs. All of these threads are bound frictionlessly together by very fine woof threads 18 of fluffy fibrous material.

Each prominent thread 16 comprises an elastic filament 19 of rubber or the like, covered with one or more spiraling fibrous filaments 20, 22, etc. (two being illustrated in Fig. 2). Each alternate thread 17 comprises one or more spiraling or intertwisting fibrous filaments. The purpose of the spiral formation is to permit the fibrous filaments to elongate and contract with the elastic filaments. The woof threads 18 preferably are substantially straight. The fibrous material may be rayon or any other suitable material—even glass—that can be spun into fine substantially frictionless threads.

From the foregoing it will be seen that I have devised a shoulder strap that is light, and comfortable, due to free sliding and elasticity in one direction only, yet that is sturdy and long wearing. The tubular construction from a flat strip imparts strength and permanence of shape to the strap, yet, due to the slight looseness and arrangement of the stitching 15, the latter does not detract from the longitudinal elasticity of the strap.

The elastic straps need not, of course, extend from end to end of the suspenders, but may consist of shorter sections inserted in the middle to pass over the shoulders.

I wish to be limited in customary manner only by reasonably liberal interpretation of the appended claims.

What is claimed is:

1. A hollow elastic strap for shoulder engaging portions of braces and analogous devices, comprising a flat strip of elastic fabric folded longitudinally at opposite sides into overlapping relationship to form a hollow strap of uniform width presenting the front face of the elastic fabric at the front and back of the hollow strap, one of the overlapped portions being folded back on itself and secured to the other portion of the overlap concealing the attached portions within the hollow strap and forming a seam of three thicknesses, said elastic fabric comprising parallel longitudinal elastic threads consisting of smoothly covered elastic filaments, long spiraling fine fibrous threads alternating in parallelism with the elastic threads, said elastic threads forming prominent ribs at the front face of the fabric, and fine inelastic cross threads interwoven with the elastic threads and holding the same in spaced parallelism without affecting the longitudinal stretching of the elastic threads and maintaining the hollow strap in normal uniform width.

2. A hollow elastic strap for shoulder engaging portions of braces and analogous devices, comprising a flat strip of elastic fabric folded longitudinally at opposite sides into overlapping relationship to form a hollow strap of uniform width, the lateral edges of the strip being secured

together interiorly of the hollow strap, said elastic fabric comprising parallel longitudinal elastic threads consisting of smoothly covered elastic filaments, long spiraling fine fibrous threads alternating in parallelism with the elastic threads, said elastic threads forming prominent ribs at the front face of the fabric and fine elastic cross threads interwoven with the elastic threads and holding the same in spaced parallelism without affecting the longitudinal stretching of the elastic threads and maintaining the hollow strap in normal uniform width.

3. A hollow elastic strap for shoulder engaging portions of braces and analogous devices, comprising a flat strip of elastic fabric folded longitudinally at opposite sides into overlapping relationship to form a hollow strap of uniform width, the lateral edges of the strip being secured together, said elastic fabric comprising parallel longitudinal elastic threads consisting of smoothly covered elastic filaments, long spiraling fine fibrous threads alternating in parallelism with the elastic threads, said elastic threads forming prominent ribs at the front face of the fabric and fine inelastic cross threads interwoven with the elastic threads and holding the same in spaced parallelism without affecting the longitudinal stretching of the elastic threads and maintaining the hollow strap in normal uniform width.
